ATTYS.

UNITED STATES PATENT OFFICE.

JOHN MAYHER, OF EASTHAMPTON, MASSACHUSETTS.

PUMP.

SPECIFICATION forming part of Letters Patent No. 244,641, dated July 19, 1881.

Application filed November 1, 1880. (No model.)

To all whom it may concern:

Be it known that I, JOHN MAYHER, of Easthampton, in the county of Hampshire and State of Massachusetts, have invented new and useful Improvements in Pumps; and I do hereby declare the following to be a full, clear, and exact description of the same, reference being had to the accompanying drawing, and to the letters of reference marked thereon.

10 This invention relates to that class of pumps known as "bucket-plungers," and it consists, mainly, in certain special details of construction, fully described hereinafter, by means of which access to the valve-chamber is more readily obtained and the cost of production is reduced.

In the drawing is represented a vertical sectional elevation of the base portion of a pump having my improvements applied thereto.

20 To enable others skilled in the art to make my improved pump, I will proceed to describe fully the construction of the same.

A represents the base portion of the pump. B represents the lower valve, and b the valve-seat provided with the guide-stem b'. The valve-seat is itself supported, it will be observed, by the division-wall or diaphragm b². C represents the upper valve, and c the valve-seat provided with the guide-stem c'. The 30 valve-seat itself, it will be observed, is supported by the division-wall or diaphragm c². The opening in the diaphragm c² is larger in area than the valve below it, and hence the latter may be readily inserted or removed through the former when desired.

D represents a bolt extending downward through the air-chamber d, the lower end of

which is adapted to bear upon the upper end of the guide-stem of the upper valve-seat.

d' d' represent screws or bolts, by means of 40 which the air-chamber is removably secured to the base portion of the pump.

Some of the advantages of the described construction are as follows: The guide-stem of the lower valve-seat being held in place by the 45 guide-stem of the upper valve-seat, and the latter being held in place by the air-chamber bolt, it follows that these are all perfectly held simply by the bolts which secure the air-chamber to the base of the pump; consequently, 50 by simply removing these bolts, all the valve parts are released, so that they may be readily removed. The upper valve-seat, also, may be tightened, if desired, without removing the air-chamber, by simply screwing down the bolt D. 55

Having thus fully described my invention, what I claim as new, and desire to secure by Letters Patent, is—

In combination with the upper valve-seat, c, having the guide-stem c', the bolt D, the upper 60 end of which extends through the top of the air-chamber, and the lower end of which bears on the guide-stem c', the construction being such that the valve-seat may be tightened without removing the air-chamber, and also 65 be securely held from displacement when struck by the lower valve in the upward movement of the latter.

This specification signed and witnessed this 22d day of October, 1880.

JNO. MAYHER.
